UNITED STATES PATENT OFFICE

GEORGE W. CRAVEN, OF MACON, GEORGIA, ASSIGNOR TO J. S. SCHOFIELD'S SONS CO.,
OF MACON, GEORGIA

LOCK FOR WATER-METER BOXES AND THE LIKE

Application filed January 26, 1929. Serial No. 335,298.

This invention relates to a lock designed primarily for use in connection with water meter boxes and similar structures, one of the objects being to provide a simple and efficient lock which can be combined readily with the cast cover of a meter box.

A further object is to provide a lock utilizing a spring actuated bolt, the spring being positioned where it will not be exposed to moisture entering the key hole in the cover, the mounting of the spring being such as to allow the same to be readily renewed if broken.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a horizontal section through a meter box showing the cover and its lock in bottom plan.

Figure 2 is a section on line 2--2, Figure 1.

Figure 3 is a section on line 3--3, Figure 1.

Figure 4 is a section on line 4--4, Figure 1.

Referring to the figures by characters of reference, 1 designates a meter box open at the top and provided with a rib 2 extending inwardly from the walls thereof forming a seat 3 for the reception of the edge portion of a removable cover 4. This cover is formed in a single casting provided, at one end, with a depending outturned lug 5 adapted, when the cover is in closed position, to extend under a portion of the rib 2 as shown in Figure 3.

Parallel longitudinal reinforcing ribs 6 are cast on the bottom surface of the cover and these ribs are connected at intermediate points by cross ribs 7 and 8 also cast integral with the cover. The rib 8 is formed with an angular opening 9 and extending from

this rib adjacent one side of the opening is a short stud 10.

An ear 11 is cast integral with the cover 4 between the apertured portion of the rib 8 and the adjacent end of the cover and in this ear is formed an angular opening 12. An angular bolt 13 is slidably mounted in the openings 9 and 12 and has oppositely extending fingers 14 and 15 located between the rib 8 and the ear 11. A stud 16 extends from finger 15 and is adapted to project into one end of a coiled spring 17 the other end of which receives the stud 10. This spring serves to hold the finger 15 normally pressed against the ear 11 at which time the outer end of the bolt 13 will be positioned under and in engagement with the adjacent portion of rib 2. This outer end of the bolt can be so shaped as to fit snugly under the rib as shown. When the bolt is in projected or rib engaging position as shown in figures 1 and 3 the finger 14 will be held close to a key hole 18 formed in the cover. Thus when a key properly proportioned is inserted into the key hole 18 and turned, it will come against finger 14 and thrust the bolt 13 backwardly against the action of the spring 17. As soon as the key is removed, however, this spring will return the parts to their normal positions as shown in Figure 1.

In assembling the lock with the cast cover 4 the bolt 13 is inserted into the opening 9 and, in order to allow this bolt to be tilted to escape ear 11 while the bolt is being inserted, the opening 9 is made slightly larger than would otherwise be necessary. This is shown in Figure 3. After the bolt has been inserted backwardly through opening 9 a sufficient distance to bring its other end back of the ear 11, said bolt can be inserted forwardly through the opening 12 in the ear until finger 15 comes against said ear. The spring 17, after being placed under compression, is inserted between rib 8 and finger 15 and placed in engagement with the studs 10 and 16. The parts are thus assembled and ready for use.

To prevent a key from moving against finger 14 and past said finger so as to become disengaged therefrom, a guard finger

or projection 19 may be cast on the cover. Thus after the key has thrust finger 14 backwardly a sufficient distance to disengage the bolt 13 from rib 2, said key will come against this pin 19 and be held against further rotation.

Importance is attached to the fact that this cover can be readily cast and that the bolt can be assembled therewith without requiring the use of rivets, special fastening devices or the like. Should the spring 17 break it will drop out of place or can be easily removed and another one substituted therefor. This would not be true should the broken spring be mounted on the bolt 13. In that event, should the spring break, it would be in the way and would interfere with the operation of the bolt as well as its removal for the purpose of applying another spring.

20. What is claimed is:

The combination with a box cover having a key hole and a transverse apertured rib cast integral with the bottom of the cover, of an ear cast integral with the bottom of the cover, a straight bolt angular in cross section slidably mounted in and held against rotation by the rib and ear, a laterally extending finger on the bolt, said bolt being extended between the key hole and the finger, 25 a coiled compression spring interposed between the finger and the rib for holding the bolt normally projected beyond the edge of the cover, studs on the rib and finger projecting into the ends of the spring, and a key- 30 engaging finger extending from the bolt at that side thereof opposite to the first-named finger and toward the key hole, said bolt being slidably into and out of engagement with the rib and ear when the spring is removed, 35 the bolt-receiving opening in the rib being 40 oversize to permit tilting of the bolt when disengaged from the ear.

In testimony that I claim the foregoing as my own, I have hereto affixed my signature.

45 GEORGE W. CRAVEN.
